UNITED STATES PATENT OFFICE

161,534

PEELER

Sheldon P. Riley, Newport Beach, Calif., assignor
to C. P. Colbert, Burbank, Calif.

Application June 10, 1949, Serial No. 3,175

Term of patent 3½ years

(Cl. D22—3)

To all whom it may concern:

Be it known that I, Sheldon P. Riley, a citizen of the United States, residing at Newport Beach, in the county of Orange and State of California, have invented a new, original, and ornamental Design for Peeler, of which the following is a specification, reference being had to the accompanying drawings, forming a part thereof.

Figure 1 is a perspective view of a peeler embodying my new design;

Figure 2 is a side elevational view thereof;

Figure 3 is a top plan view thereof;

Figure 4 is an end view thereof; and

Figure 5 is a cross sectional view taken on the line 5—5 of Figure 2.

I claim:

The ornamental design for a peeler, as shown.
SHELDON P. RILEY.
